ENGINE PISTON

John Bezosky, Binghamton, N. Y.

Application December 5, 1935, Serial No. 53,073

2 Claims. (CL 309—7)

My invention relates to an engine piston designed primarily for use in connection with internal combustion engines, but it is to be understood that a piston structure, in accordance with my invention, may be employed in any connection for which it is found applicable.

The object of my invention is to provide, in a manner as hereinafter set forth, a piston structure which eliminates the tendency to slap during its reciprocation, as well as not only preventing oil leakage when the rings become worn but also reducing ring replacement to a minimum.

Further objects of my invention are to provide, in a manner as hereinafter set forth, a piston structure which is simple in its construction and arrangement, strong, durable, compact, readily assembled, thoroughly efficient when in use, conveniently repaired when occasion requires, and comparatively inexpensive to manufacture.

With the foregoing and other objects which may hereinafter appear, my invention consists of the novel construction, combination and arrangement of parts as will be more specifically described and as are illustrated in the accompanying drawing wherein are shown embodiments of my invention, but it is to be understood that changes, variations and modifications may be resorted to which fall within the scope of my invention as claimed.

30 In the drawing:

Figure 1 is a vertical sectional view of the piston structure,

Figure 2 is a cross-sectional view of the ring element,

Figure 3 is a fragmentary view of the piston body with the head thereof and ring element removed,

Figure 4 is a top plan view of the structure shown in Figure 3,

Figure 5 is a top plan view of the ring element,

Figure 6 is a top plan view of the piston structure, and

Figure 7 is a fragmentary view in vertical section of a modified form of piston structure in accordance with my invention.

A piston structure, in accordance with my invention, includes a one-piece tubular body 8 open at each end and formed of a follower end part 9, intermediate parts 10, 11, 12 and 13, a frusto-tapered part 14 and a leading end part 15. The part 9 merges into the rear end of and is of greater inner diameter than part 10. The latter gradually decreases in inner diameter from its rear to its forward end. The part 10 is of greater thickness and of less length than part 9. The forward

end of part 10 merges into the rear end of part 11. The latter is of materially greater length than part 10 and is of uniform inner diameter throughout. The thickness of part 11 corresponds throughout to the point of greatest thickness of part 10. The forward end of part 11 merges into the rear end of part 12. The latter gradually decreases in inner diameter from its rear to its forward end and is of less length than part 10. The part 12 is of greater thickness and of materially less length than the part 11. The part 12 at its forward end merges into the rear end of part 13. The latter is of greater length than part 12 and is of uniform inner diameter throughout. The thickness of part 13 corresponds throughout to the point of greatest thickness of part 12. The forward end of part 13 merges into the rear end of part 14. The inner diameter of the part 14 gradually decreases from its rear to its forward end. The part 14 is formed with an endless rabbet in its outer face to provide a portion 16 of reduced thickness, a seat 17 and a peripheral shoulder 18. The inner and outer diameters of the part 15 are less than that of the other parts of body 8. The part 15 is inset with respect to the other parts of the body 8 and is disposed in angular relation with respect to the outer end of the part 14. The latter has its forward end merge into the outer lower corner of the part 15. The portion 16 of part 14 is arranged forwardly with respect to the remaining portion of said part 14. The part 15 is disposed inwardly at right angles relative to parts 9 to 13 both inclusive.

The part 13 is formed with a leading and a follower piston ring receiving groove indicated 35 at 19 and 20, respectively. Within the grooves 19 and 20 are arranged piston rings 21 of known construction. Leading from the groove 19 and opening into the body 8 are inclined oil return ducts 22. The part 13 is formed with a pair of 40 diametrically opposed elongated rectangular slots 23 (only one of which is shown) and which constitute spaces for oil return. The slots 23 open into the groove 20.

The outer periphery of the thickest portion of 45 the part 14 is formed with a circumferentially extending row of substantially V-shaped grooves 24 which merge into each other, as at 25. At the point of emergence of one groove 24 with another a port 26 is formed in part 14 which inclines 50 downwardly relative to part 13 and opens into the body 8. Preferably the number of ports 26 will be sixteen, but this number may be increased or diminished if desired. The ports 26 are spaced from the leading end of the thickest portion of 55

the part 14. The ports 26 provide for the return of the oil collected in the grooves 24.

Encompassing the part 14, as well as the outer edge of the part 15, is a diagonally split ring element 27 having its outer side edge 28 of uniform outer diameter. The split in the element 27 is indicated at 29. The element 27 is formed of a follower portion 30, an intermediate portion 31 and a leading portion 32. The inner edge of the portion 31 is inset with respect to the portion 30. The latter gradually increases in thickness from its rear to its forward end and merges into the rear end of portion 31. The portion 31 gradually increases in thickness from its rear end to its forward end and merges into the rear end of the portion 32. The junction of the portions 30, 31 forms element 27 with an internal annular shoulder 33 due to the fact that at the point of merger of portion 30 with portion 31 the rear end of portion 31 is of greater thickness than the forward end of portion 30. The portion 32 is of uniform thickness and of less length than the portion 31. The latter is of less length than the portion 30. The construction as aforesaid provides the inner side edge of element 27 with a leading edge portion 34 of uniform diameter, an intermediate edge portion 35 gradually decreasing in diameter from its rear end to the edge portion 34 and a follower edge portion 36 offset with respect to edge portion 35 and gradually decreasing in diameter from its rear end to the inner end of the shoulder 33. The element 27, when in encompassing relation relative to part 14, has its inner edge portion 34 opposing the seat 17, its shoulder 33 opposing the shoulder 18 and its edge portion 36 opposing the grooved outer face of the thickest portion of the part 14.

The piston structure includes a head element 37 which is in the form of a disc 38 provided on its follower face with an inset annular flange 39. The disc 38 is formed with a series of countersunk threaded openings 40 which are adapted to align with threaded openings 41 formed in the part 15 of the body 8. The disc 38 is positioned against the leading face of the part 15 of portion 8 and when so arranged the flange 39 is encompassed by the inner edge of the said part 15. When in the position aforesaid, the openings 40 align with the openings 41. Extending through the aligning openings 40, 41 and threadededly engaging with the disc 38 and part 15 of body 8 are threaded holdfast devices 42 which are flush with the leading face of the head element 37. The latter, when secured to the part 15 of body 8, provides, in connection with said part 15, as well as the part 14 of body 8, an annular groove 43 of substantially right angled triangular form in cross-section. The ring element 27 is mounted in the groove 43.

When the piston structure is in operation, the ring element 27 engages the seat 17 and shoulder 18 whereby it is prevented from being forced rearwardly completely out of the groove 43. The cross-sectional dimension of the element 27 is less than the cross-sectional dimension of the groove 43 thereby preventing a play of such element 27 during the operation of the piston structure.

The modified form of the piston structure shown in Figure 7 will be the same as the form

shown in Figure 1, with the exception that the part 44 which corresponds to the part 15 of the tubular body 8 has its inner edge formed with screw threads 45 and that the flange 46, which corresponds to the flange 39 of head element 37, will have its outer edge provided with screw threads 47. The threads 45 and 47 coact to connect the head element 48 to the part 44. In Figure 7 the tubular body is indicated at 49. Lock screws 49a are employed in lieu of the holdfast devices 42 and which abut the part 44. The element 48 has a pair of sockets 50, only one of which is shown, to receive a spanner wrench for facilitating the positioning of element 48. Otherwise than that as stated, the structure shown in Figure 7 will be similar in all respects to the structure shown in Figure 1.

The ring element 27 coacts with the head element 37 and tubular body 8 in a manner to eliminate the tendency of the piston to slap and further to reduce oil leakage that occurs when the piston ring has become worn. The oil gathered during the reciprocation of the piston structure is returned by the ducts 22, slots 23, ports 26 and grooves 24 to the interior of the tubular body 8.

Shims may be employed for taking up wear relative to the ring element 27, head element 37 or 48 and part 15 or 44, and in this connection a shim 51 is shown in Figure 1.

What I claim is:

1. A piston structure comprising a tubular body formed at its leading end with a tapered part merging at its forward end into an inwardly extending part, a head element secured against said inwardly extending part and forming in connection with said tapered part an annular groove, said tapered part being formed with an annular peripheral shoulder and a seat, a split ring element mounted in said groove and provided with means on its inner face to engage said seat and shoulder, said ring element having its cross-sectional contour corresponding with the cross-sectional contour of said groove, and said tapered part rearwardly of its shoulder being formed in its outer periphery with a circumferentially extending row of V-shaped grooves merging into each other and ports at the points of emergence of the grooves of said row, said ports opening into the interior of said body.

2. A piston structure including a tubular body having its leading end terminal portion formed with a tapered outer periphery, a head element secured against and extended laterally from the leading end of said body, said leading end terminal portion forming in connection with the extended portion of said head an annular groove, said tapered part being formed on and intermediate the ends of its outer periphery with an annular seat and an annular shoulder rearwardly of the seat, a split ring element mounted in said groove and provided with means on its inner face to engage said seat and shoulder, and said tapered part rearwardly of said shoulder being formed respectively in its outer periphery with a circumferentially extending row of lubricant collecting grooves communicating with each other and in its body with spaced ports opening into the grooves of said row and into the interior of said body.
